UNITED STATES PATENT OFFICE.

ARTHUR T. PRESCOTT, OF ARLINGTON, MASSACHUSETTS.

AMUSEMENT DEVICE.

SPECIFICATION forming part of Letters Patent No. 712,407, dated October 28, 1902

Application filed May 31, 1902. Serial No. 109,620. (No model.)

To all whom it may concern:

Be it known that I, ARTHUR T. PRESCOTT, a citizen of the United States, residing at Arlington, county of Middlesex, State of Massachusetts, have invented an Improvement in Amusement Devices, of which the following description, in connection with the accompanying drawings, is a specification, like characters on the drawings representing like parts.

10 This invention relates to amusement devices of the roller-coaster type, and has for its object to provide a bicycle-track having a downward incline and a vertically-arranged loop portion whereby a bicycle-rider may in 15 traversing the track descend the downward incline by gravity and pass around the interior of the loop, the force necessary to carry him through the loop being acquired during the descent of the downwardly-inclined portion 20 of the track and the rider being held to the track in traversing the loop by centrifugal force.

The construction of the track that I preferably employ comprises a plurality of girders 25 running longitudinally of the track, upon which is supported and to which is secured the floor portion of the track upon which the bicycle travels. I will preferably construct a part of or the entire floor portion in sections, which are independent from each other 30 and each of which is detachably secured to the girders, whereby any one section may be readily removed or replaced. Inasmuch as the bicycle in traversing the loop has to be 35 guided by the rider, I prefer to make that portion of the track constituting the vertically-arranged loop wider than the downwardly-inclined portion, so as to allow the rider some latitude in making the circle of 40 the loop. I also will preferably provide the floor portion of the track with a guiding-stripe, which runs longitudinally of the track and which will be of some color contrasting 45 with the color of the floor portion of the track, this guiding-stripe serving to assist the rider in keeping the center of the track while passing through the loop.

Other details of the invention will be more particularly hereinafter described, and pointed out in the claims.

Figure 1 shows a perspective view of my improved amusement device. Fig. 2 is a side

elevation of the loop portion thereof. Fig. 3 is a detail showing the manner of securing the floor-sections of the track to the girders. 55 Fig. 4 is a perspective view of the framework for the loop. Fig. 5 is a detail showing one way in which the downwardly-inclined portion of the track may be supported. Fig. 6 is a plan view of the loop portion of the track. 60 Fig. 7 is a detail of the guiding-stripe. Fig. 8 illustrates one braking device for gradually stopping the rider after he has been through the loop, and Fig. 9 is a detail of a floor-section. 65

The general arrangement of the track is somewhat similar to that illustrated in patent to Edwin Prescott, No. 667,455, patented February 5, 1901, in that it has the downwardly-inclined portion 3 and the vertically-arranged 70 loop portion 4. In this instance, however, the track instead of having rails upon which a car is adapted to run, as in said patent, has a continuous floor-surface over which a bicycle is adapted to travel.

One convenient way of constructing this bicycle-track is to provide a series of girders which extend longitudinally of the track and on which the floor-surface is supported. In the drawings the girders are designated by 5, 80 and they extend from the top of the track down the inclined portion 3, and are then bent upwardly, rearwardly, and downwardly to form the loop portion 4. These girders may be of any suitable size and shape; but 85 I have found from practice that angle-iron answers all purposes, and I will preferably therefore use this material. The floor-surface, especially that portion thereof constituting the loop, will preferably be made in 90 sections 6, and each section will comprise a plurality of boards extending transversely of the track and secured to a backing strip or cleat, and the various floor-sections when completed will be detachably secured to the 95 girders 5, which form the framework of the track. Fig. 9 shows a portion of one section of the floor, which, as illustrated, comprises the transversely-extending boards 6, which are secured to the backing strips or cleats 7, 100 situated on the back of the section, said cleats being arranged to extend longitudinally of the track. If desired, the floor-surface of the downward incline may be rigidly secured to

the girders, and, in fact, my invention would not be departed from if the entire extent of the floor-surface were thus secured to the girders. The object in making the loop portion of the floor-surface in sections detachably secured to the girders is to facilitate the erection of the loop portion of the track and also to allow the sections to be easily removed in case the amusement device is used in connection with a circus or in any other place where the sections when in place would obstruct the view of some part of the performance. In such instance the floor-sections constituting the loop portion of the track will be removed when the track is not to be used, but can be readily replaced when the performance on the track is being carried on.

Fig. 3 shows one simple way of detachably securing the various floor-sections to the girders, and, in said figure, 9 designates a suitable button which is secured to the back side of the floor-section, and the nose 10 of which when in operative position locks over the horizontal flange of the angle-iron girder. There will preferably be four or more of these buttons on each floor-section, as seen in Fig. 6. Any other suitable means may be employed, however, for securing the floor-sections to the girders without departing from the spirit of my invention. The advantage secured by the use of the buttons 9 is the great facility with which the floor-sections may be put in place and removed.

The backing strips or cleats 7 of adjacent floor-sections are provided with interlocking ends, as best seen in Fig. 2, wherein one end of the backing-strip on each section has a projection 11, which enters a corresponding recess in the end of the next adjacent backing-strip, this construction serving to assist in securely holding the floor-sections in place. The floor-sections may, if desired, be further secured in place by bolting the backing-strips to the vertical flange of the angle-iron, as seen at 12 in Figs. 3 and 9.

Since the bicycle in making the trip over the track has to be guided entirely by the rider, I have found it desirable for the safety of the rider to make the loop portion of the track wider than the downwardly-inclined portion, and, as illustrated in Figs. 1, 6, and 7, the widening of the track begins at substantially the point where the downwardly-inclined portion 3 merges into the loop portion 4 or at about the point 13 in Fig. 2. From the point 13 through the first half 14 of the loop and into the last half 15^a thereof the track is of a progressively-increased width, as best seen in Fig. 6, this increase of width allowing ample leeway to insure the rider safely guiding his wheel through the loop. In order to securely support the wider portion of the track, I will throughout the loop portion preferably employ three girders 5, as best seen in Fig. 4. To further assist the rider in guiding his bicycle over the course, I may employ a guiding-stripe 15, which may

be either painted on or otherwise secured to the floor-section and which will preferably be of a color contrasting with the floor. So long as the rider follows the guiding-stripe closely he knows that he is traveling at the center of the track, and is therefore in no danger of running off the same.

The loop portion of the track must necessarily be in the form of a spiral, as will be obvious, and it is necessary, therefore, for the rider as he enters the loop to turn his wheel slightly in the direction of a spiral in order to carry him safely through the loop, and in order that he may have some indication as to the proper instant at which to begin to guide his bicycle through the loop I will preferably provide a guiding-stripe at the entering portion of the loop with an indication-mark which serves to indicate to the rider when he passes over the same that he must turn the steering-wheel of his bicycle slightly. Fig. 7 illustrates one form of such indication-mark, it being in the nature of a spur 16, projecting from one side of the guiding-stripe and indicating to the rider the point where and the direction in which he must turn his wheel. This indication-mark will be situated at about the point *a*, Fig. 1, of the track.

I prefer to make the loop portion of the track of substantially the same design as that shown in the patent to Prescott, No. 667,455, above referred to—that is, the track at the foot of the downward incline or at about the point *m*, Fig. 2, merges into a curve of progressively-decreasing radii which passes into and forms the first half 14 of the loop, while commencing substantially at the horizontal diameter of the loop and extending to the end of the track the curve is one of progressively-increasing radii. This method of constructing the track brings the crossing-point *o* of the track or the lowest point of the loop above the curved portions *r* and *s* of the track leading into and out from the loop, so that the lowest portions of the inclines leading to and out from the loop are in a plane below any portion of the loop. The object in this special form of loop is to provide an easy curve leading into and out from the loop whereby the rider experiences no shock or jar in his passage from the downward incline into the loop, all as more fully set forth in said above-mentioned patent. While it is preferable to thus construct the loop, yet my invention would not be departed from if the loop were some other shape.

The loop portion of the track may be held and braced in any suitable way; but I prefer to employ the means shown in Fig. 4, since it occupies a minimum amount of space and operates to thoroughly brace the structure. Beneath the loop portion of the track I will preferably employ a foundation-work comprising the longitudinal sills 20 and the cross-sills 21, these sills being of metal or wood or any other suitable material. Extending trans-

versely of the sill structure is the cross-girder 22, which is raised slightly from the sills and on which the girders 5 rest at the point *o*, where they cross each other and extend into and leave the loop. Secured to each cross-sill 21 are the vertical braces 23, which extend up either side of the loop and which are tied together at their upper ends by the tie members 24. The uprights 23 of the frame are tangent to the curved portions of the girders which form the loop and are secured thereto in any suitable way, and the tie members 24 are also tangent to the loop and secured to the girders 5, as seen in Figs. 2 and 4. The sills 21, the uprights 23, and the tie members 24 thus form a substantially rectangular frame, which incloses the loop portion of the track and which serves to securely brace the same against any strains incident to passage of the 20 rider through the loop.

It is my intention to construct this apparatus so that it can be employed as part of a circus equipment, and when used in this way it must be constructed so as to be readily set 25 up or taken down. Accordingly I will preferably provide the uprights 23 with eyes at their lower ends, which may be hinged to corresponding eyes on the sills 21, and the tie members 24 will be provided with some suitable 30 means for securing them to the uprights which permits the structure to be readily set up or taken down. The curved portions of the girders 5, which form the loop, are made in sections, one section of each of the girders 35 including the upper half of the loop and extending from the point *b* to the point *c*. These substantially semicircular portions of the girders, which I have designated *d*, will preferably be fixedly secured to the tie members 40 24. In setting up the loop portion of the track the uprights 23 can be laid down on the ground and the eyes therein brought to register with the eyes on the sills 21, when hinge-bolts can be passed through the aligned eyes, 45 thus hinging the uprights to the sills. Thereafter the uprights will be turned about their hinges into their upright position, when the cross members 24, with the curved sections *d* of the girders secured thereto, will be brought 50 into position and secured to the upper ends of the uprights. Subsequently the portions *e* and *f* of the girders forming the lower half of the loop will be brought into position and their ends detachably secured to the ends of 55 the sections *d* in some suitable way, and the uprights 23 will then be bolted or otherwise secured to the girders where they come tangent thereto. After the frame has thus been constructed, as shown in Fig. 4, the floor-sections 40 will be detachably secured in place, 60 as above described, when the loop portion of the track is ready for operation.

The downwardly-inclined portion of the track may be made in two or more sections, 65 as desired, and I will preferably make the same with the upper fixed section 31 and the

lower section 32, which is hinged to the section 31 in some suitable way, as at 33, and the lower end of which hinge-section meets the section of the loop portion of the track 70 which is supported on the girder-sections *f*. The downwardly-inclined portion of the track may be supported in any suitable way, but preferably will be supported on struts 25, which rest at their lower ends on the ground 75 and at their upper ends set into sockets 26 upon the under side of the track. The purpose in making the section 32 of the track hinged is so that it may be raised, as shown in dotted lines, Fig. 2, so as not to obstruct 80 the view of other parts of the performance when the device is used in connection with a circus. In order to stiffen the hinged section 31, I will preferably truss the same, as at 34.

It is necessary to provide some braking device or similar means for gradually stopping the rider after he emerges from the loop, and in Fig. 8 I have illustrated one simple device for accomplishing this. In said figure 41 designates suitable posts situated either 85 side of the path of the rider as he emerges from the loop, and 42 designates a suitable rope stretched across the posts at the proper height to engage the head of the bicycle. The rope extends backwardly from the posts 90 toward the loop portion, as at 43, and to each end of the rope is secured a chain 44, which is bent back and extends forwardly 95 toward the posts 41. The bicycle upon striking the rope 42 will drag the same forward, 100 as will be obvious, and the first movement of the rope will require comparatively little power, and consequently retard the bicycle very little, since the rope itself is comparatively light; but as the bicycle drags the 105 rope farther in the direction of the arrow, Fig. 8, one link after the other of the chains 44 is brought into line with the longitudinal-extending portions 43 of the rope, and the weight, therefore, which is attached to the 110 rope and which is being dragged is a constantly increasing weight. This device therefore operates to bring a gradually-increasing retarding force upon the bicycle 115 and will thus stop the rider without any sudden shock or jar.

The bicycle which, preferably, will be employed with this device will have no cranks, but will merely be provided with stirrups; into which the rider will place his feet and by 120 which he can brace himself during his ride.

The operation of the device will be apparent from the drawings and from the foregoing description. In starting, the rider will stand upon the blocks 50, situated at either 125 side of the starting-point of the track, which blocks raise the rider sufficiently so that an attendant may place the bicycle in position to receive the rider. The rider then takes his seat upon the bicycle and removes his 130 feet from the blocks 50, placing them in the stirrups, and is off. The length of the down-

ward incline is such that sufficient momentum is acquired by the rider to carry him up into and through the loop, the rider in traversing the upper portion of the loop of course being bottom side up, but being held to the track by centrifugal action. The guiding-stripe 15 and indication-mark 16 serve to properly guide the rider through the loop, as above described, and as he emerges from the loop the retarding device (illustrated in Fig. 8) will gradually bring him to a stop.

While I have herein shown the loop portion of my track as used in connection with a downwardly-inclined portion, yet since the function of a downwardly-inclined portion is to allow the rider to acquire sufficient speed before entering the loop to carry him through the loop it will be obvious that the loop portion of my track can be used without the downwardly-inclined portion, provided some suitable means are employed to give the rider sufficient momentum before entering the loop to carry him through the loop. As one way of giving the rider the requisite speed for entering the loop without the use of the downwardly-inclined portion of the track I would suggest the employment of a motor-bicycle.

My invention, therefore, is not necessarily limited to the construction of the loop in connection with the downwardly-inclined portion of the track, as I would consider as coming within my invention a track having a loop portion as above described without reference to the construction or position of the portion of the track leading into the loop.

Having described my invention, what I claim as new, and desire to secure by Letters Patent, is—

1. An amusement device comprising a track having a smooth continuous surface of sufficient width to permit a bicycle to travel thereover, and presenting a downward incline and a vertically-arranged loop.

2. An amusement device comprising a bicycle-track constructed to present a downward incline and a vertically-arranged loop, the portion of the track forming the loop being wider than the downwardly-inclined portion.

3. An amusement device comprising a bicycle-track constructed to present a downwardly-inclined portion and a vertically-arranged loop, the portion of the track forming the loop having a progressively-increasing width from the foot of the downwardly-inclined portion.

4. An amusement device comprising a bicycle-track having a smooth continuous surface of sufficient width to permit a bicycle to travel thereover, said track being provided with a guiding-stripe extending the length thereof.

5. An amusement device comprising a bicycle-track having a downwardly-inclined portion and a vertically-arranged loop, and a guiding-stripe extending the length of the track.

6. An amusement device comprising a bicy-

cle-track, having a downwardly-inclined portion and a vertically-arranged loop, and a guiding-stripe extending throughout the loop portion of the track.

7. An amusement device comprising a bicycle-track having a smooth continuous surface of sufficient width to permit a bicycle to travel thereover, the said track presenting a downwardly-inclined portion and a vertically-arranged loop, and a guiding-stripe extending the length of the track, said stripe being of a color contrasting with the color of the track.

8. A bicycle-track presenting a downward incline and a vertically-arranged loop, combined with a guiding-stripe extending the length of the track, and having a directing-mark at the entering portion of the loop, to assist the rider in steering his bicycle through the loop.

9. A bicycle-track presenting a downward incline and a vertically-arranged loop, combined with a guiding-stripe extending through the loop portion of the track, said stripe having a spur to indicate to the rider the direction in which to steer his bicycle.

10. A bicycle-track having a smooth, continuous surface of sufficient width for a bicycle to travel thereover, and presenting a downwardly-inclined portion and a vertically-arranged loop, combined with means to gradually bring the bicycle of the rider to rest after it leaves the loop.

11. A bicycle-track presenting a downward incline and a vertically-arranged loop, combined with a retarding device to engage the bicycle of the rider and bring the same to rest gradually after leaving the loop.

12. A bicycle-track presenting a downward incline and a vertically-arranged loop portion, around the interior of which the rider passes, combined with a rope stretched across the path of the bicycle in position to be engaged by the latter after it has left the loop, and means whereby as the rope is dragged forward by the bicycle an increasing weight is applied thereto.

13. A bicycle-track, comprising in its construction a plurality of girders extending in the direction of its length, and a floor secured to the girders, said floor presenting a surface of sufficient width for a bicycle to travel thereover, and the track being formed to present a downwardly-inclined portion and a vertically-arranged loop.

14. A bicycle-track, comprising a downwardly-inclined portion and a vertically-arranged loop, and comprising in its construction a plurality of girders extending in the direction of the length of the track, a floor portion secured to the girders and forming a surface of sufficient width for a bicycle to travel thereover, a portion of said floor being made in sections, and means to detachably secure each section to the girders.

15. In a bicycle-track, a plurality of girders extending longitudinally of the track, said

girders having laterally-extended flanges; a floor made in sections, and buttons secured to each section and adapted to engage the flanges of the girder whereby each section is detachably secured in place.

16. In a bicycle-track, a plurality of girders extending longitudinally of the track, and constructed to present a downwardly-inclined portion and a vertically-arranged loop, and a floor supported by said girders.

17. In a bicycle-track, a plurality of girders extending longitudinally of the track, and constructed to present a downwardly-inclined portion and a vertically-arranged loop, and a floor supported by said girders, the portion of the floor forming the loop being made in sections, and means to detachably secure each section to the girders.

18. A bicycle-track presenting at some point in its course a vertically-arranged loop, the floor of the loop portion of the track being made in independently-removable sections each of which is composed of boards extending transversely of the track, and rigidly secured together by backing strips or cleats extending longitudinally of the track.

19. A bicycle-track presenting at some point in its course a vertically-arranged loop, the floor of the loop portion of the track being made in independently-removable sections each of which is composed of boards extending transversely of the track and rigidly secured together by backing strips or cleats extending longitudinally of the track, the backing-strips of adjacent sections having their ends interlocked together.

20. In an amusement device, a substantially rectangular frame, a track having a vertical loop portion forming the interior of said rectangular frame and secured thereto.

21. A bicycle-track presenting a downwardly-inclined portion, and a vertically-arranged loop portion, said downwardly-inclined portion having an upper fixed section and a lower section hinged thereto.

22. A bicycle-track presenting a downwardly-inclined portion and a vertically-arranged loop, the downwardly-inclined portion having its lower end hinged, whereby it may be raised when not in use.

23. A bicycle-track presenting a downwardly-inclined portion and a vertically-arranged loop, the downwardly-inclined portion having a movable section at its foot, and the floor of the loop portion of the track being made in sections which are removably sustained in place.

24. A bicycle-track having a smooth, continuous surface of sufficient width to permit a bicycle to travel thereover, a part of a track

being arranged to present a vertically-arranged loop.

25. In an amusement device, a bicycle-track presenting in its course a vertically-arranged loop, a portion of the track forming the loop being wider than the remainder thereof.

26. In an amusement device, a bicycle-track constructed to present at some portion of its course a vertically-arranged loop, the portion of the track forming the loop having a progressively-increasing width from the entering-point of the loop to the point of exit therefrom.

27. In an amusement device comprising a bicycle-track constructed to present at some point in its course a vertically-arranged loop, and a guiding-stripe extending through the loop.

28. In an amusement device, a bicycle-track presenting a downwardly-inclined portion, and a vertically-arranged loop, combined with a platform situated either side of the track at the starting-point, and upon which the rider may stand while the bicycle is being placed in position.

29. A bicycle-track presenting at some portion in its course a vertically-arranged loop having variable radii, the floor of the track forming the loop having a variable width.

30. A bicycle-track presenting at some portion in its course a vertically-arranged loop of variable radii, the floor of the track forming the loop having a gradually-increasing width from the entering-point of the loop to the exit therefrom.

31. A bicycle-track having a floor portion of sufficient width to enable a bicycle to travel thereover, and presenting a substantially vertical loop, the portion of the track leading into the loop having progressively-decreasing radii as it approaches the horizontal diameter of the loop.

32. A bicycle-track, having a floor portion of sufficient width to enable a bicycle to travel thereover, and presenting a substantially vertical loop, the portion of the track leading into the loop having progressively-decreasing radii as it approaches the horizontal diameter of the loop, and the portion of the track leading out from the loop having progressively-increasing radii from the horizontal diameter of the loop.

In testimony whereof I have signed my name to this specification in the presence of two subscribing witnesses.

ARTHUR T. PRESCOTT.
